Primary Examiner — Jose V Chen(74) *Attorney, Agent, or Firm* — Carlson, Gaskey & Olds, P.C.(57) **ABSTRACT**

A first pallet includes a deck and a peripheral wall extending downward from a periphery of the deck. A plurality of feet extend downward from the deck. Each of the feet includes a foot wall defining its periphery. An outer portion of each foot wall is coterminous with the peripheral wall of the deck. The deck includes an opening aligned with each of the plurality of feet. A second, wider pallet may be used with the first pallet. The second pallet may be stacked on the first pallet and vice versa. In the second pallet, the outer portion of the wall of each of the feet is spaced inward from the peripheral wall of the deck, such that the deck of the second pallet is wider than the deck of the first pallet, but the spacing and size of the feet of both decks are identical.

1
STACKABLE PALLET

BACKGROUND

Pallets generally include a deck having an upper support surface for supporting goods above a floor. A plurality of feet extend downward from the deck to provide fine openings between the feet and below the deck.

Half-pallets, typically in the range of approximately 20-24 inches by approximately 40-48 inches, may be used to provide deliveries into stores. Sometimes narrower pallets would be advantageous in certain delivery locations with tighter spaces, while sometimes wider pallets would be required for certain products.

SUMMARY

A first pallet includes a deck including an upper support surface and a peripheral wall extending downward from a periphery of the upper support surface. A plurality of feet extend downward from the deck. Each of the feet include a foot wall defining a periphery of the foot. An outer portion of each foot wall is coterminous with the peripheral wall of the deck. The deck includes an opening aligned with each of the plurality of feet. The foot wall protrudes inwardly of the respective opening to form a ledge recessed downward from the upper support surface of the deck.

A second, wider pallet may be used with the first pallet. The second pallet may be stacked on the first pallet. The second pallet has a plurality of feet extending downward from a deck having a peripheral wall. The outer portion of the wall of each of the feet is spaced inward from the peripheral wall of the deck, such that the deck of the second pallet is wider than the deck of the first pallet, but the spacing and size of the feet of both decks are identical. In this manner, a system with two different-width pallets can be used together and stacked together when empty.

BRIEF DESCRIPTION OF THE DRAWINGS

FIG. 1 is a perspective view of a pallet according to a first embodiment.

FIG. 2 is a bottom perspective view of the pallet of FIG. 1.

FIG. 3 is a section view taken along line 3-3 of FIG. 1.

FIG. 4 is a side view of the pallet of FIG. 1.

FIG. 5 is an end view of the pallet of FIG. 1.

FIG. 6 is a top view of the pallet of FIG. 1.

FIG. 7 is a bottom view of the pallet of FIG. 1.

FIG. 8 shows the pallet of FIG. 1 stacked with an identical pallet.

FIG. 9 is a side view of the pallets of FIG. 8.

FIG. 10 is an end view of the pallets of FIG. 8.

FIG. 11 is a section view taken long line 11-11 of FIG. 8.

FIG. 12 is a perspective view of a pallet according to a second embodiment.

FIG. 13 is a bottom perspective view of the pallet of FIG. 12.

FIG. 14 is a section view taken along line 14-14 of FIG. 12.

FIG. 15 is a side view of the pallet of FIG. 12.

FIG. 16 is an end view of the pallet of FIG. 12.

FIG. 17 is a top view of the pallet of FIG. 12.

FIG. 18 is a bottom view of the pallet of FIG. 12.

FIG. 19 shows the pallet of FIG. 12 stacked with an identical pallet.

FIG. 20 is a side view of the pallets of FIG. 12.

2
PALLET

FIG. 21 is an end view of the pallets of FIG. 12.

FIG. 22 is a section view taken long line 22-22 of FIG. 19.

FIG. 23 is a perspective view of the pallet of FIG. 1 stacked on the pallet of FIG. 12.

FIG. 24 is a side view of the pallets of FIG. 23.

FIG. 25 is an end view of the pallets of FIG. 23.

FIG. 26 is a section view taken along line 26-26 of FIG. 23.

FIG. 27 is a perspective view of the pallet of FIG. 12 stacked on the pallet of FIG. 1.

FIG. 28 is a side view of the pallets of FIG. 27.

FIG. 29 is an end view of the pallets of FIG. 27.

FIG. 30 is a section view taken along line 30-30 of FIG. 27.

DETAILED DESCRIPTION

A pallet 10 according to a first embodiment is shown in FIG. 1. The example pallet 10 shown is a half pallet. The pallet 10 is integrally molded as a single piece of plastic, such as by injection molding. Pallet 10 includes a deck 12 having an upper support surface 18 upon which goods can be supported. The upper surface 18 is defined by an upper planar portion 19 of the deck 12. Feet 14 or columns project downward from the deck 12 to support the deck 12 above the floor. Openings 16 are formed in the upper surface 18 of the deck 12 above each of the feet 14. The openings 16 can receive the feet 14 of an identical deck 10 stacked thereon and partially received in the deck 12 for stability.

The deck 12 further includes a peripheral rib 20 extending downward from a periphery of the upper planar portion 19. Each foot 14 includes a wall 22 defining a periphery of the foot 14. The wall 22 of each foot 14 is recessed from the upper surface of the deck 12 and terminates approximately $\frac{1}{3}$ of the height of the peripheral wall 20 of the deck 12 below the upper surface 19 of the deck 12. The upper surface of the wall 22 of each foot 14 protrudes inward of each corresponding opening 16 formed in the upper surface 18 of the deck 12 to form a ledge 24 about the entire periphery of the top of each foot 14.

An outer portion 26 of the wall 22 of each foot 14 is coterminous with the adjacent portion of the peripheral wall 20 of the deck 12. This coterminous outer portion 26 of wall 22 and the peripheral wall 20 does not extend upward to the plane containing the upper surface 19 of the deck 12, but rather is recessed downward therefrom with the rest of the wall 22 of the foot 14. The outer portion 26 of the wall 22 of each foot 14 is in the vertical plane of the outer peripheral wall 20 of the deck 12. The outer portion 26 of the wall 22 of each foot 14 may be corrugated for stiffness and strength, as shown. A plurality of ribs 28 protrude inward from the wall 22 of each foot 14 with an uppermost surface in the same plane as the uppermost surface of the ledge 24.

FIG. 2 is a bottom perspective view of the pallet 10. The pallet 10 includes a plurality of intersection ribs 30 extending downward from the upper planar portion 19 (FIG. 1) of the deck 12. The ribs 30 extend downward to a plane containing the lowermost edge of the peripheral wall 20.

FIG. 3 is a section view through one of the feet 14 of the pallet of FIG. 1, taken along line 3-3 of FIG. 1. As shown, the ledge 24 is recessed downward from the upper planar portion 19 of the deck 12. The outer portion 26 of the wall 22 of the foot 14 is coterminous with the peripheral wall 20 of the deck 12. As a result, each recess 16 is open to the outside or the periphery of the pallet 10.

FIG. 4 is a side view of the pallet 10 of FIG. 1. FIG. 5 is an end view of the pallet 10 of FIG. 1. FIG. 6 is a top view of the pallet 10 of FIG. 1. FIG. 7 is a bottom view of the pallet 10 of FIG. 1.

FIG. 8 is a perspective view of the pallet 10 of FIG. 1 with an identical pallet 10 stacked thereon. The feet 14 of the upper pallet 10 are received in the recesses 16 in the deck 12 of the lower pallet 10. The feet 14 of the upper pallet 10 are stacked on the ledge 24 and ribs 28. The corrugations in the outer portion 26 of the wall 22 of the feet 16 of the upper pallet 10 mate with the corrugations on the feet 14 of the lower pallet 10. The recesses 16 reduce the overall stacking height of the empty pallets 10 and increase the stability of the stack.

FIG. 9 is a side view of the stacked pallets 10. FIG. 10 is an end view of the stacked pallets 10.

FIG. 11 is a section view through the feet 14 of the stacked pallets 10. The feet 14 of the upper pallet 10 are received in the recesses 16 of the lower pallet 10, with the walls 22 of the feet 14 of the upper pallet 10 supported on the ledge 24 of the feet 14 of the lower pallet 10, i.e. the upper surfaces of the walls 22 of the feet 14 of the lower pallet 10.

A pallet 110 according to a second embodiment is shown in FIG. 12. The example pallet 110 shown is a half pallet. The pallet 110 is identical to the pallet 10 of FIGS. 1-11 except as described below or shown in the Figures. As will be explained further below, the two pallets 10, 110 together are part of a system and can stack with one another. In particular, the pallet 110 has a wider deck 112 than the pallet 10 but has identical spacing of feet 114. For example, the pallet 110 may have a deck 112 width of 20.7 inches, while the pallet 10 may have a deck 12 width of 19 inches.

The pallet 110 is integrally molded as a single piece of plastic, such as by injection molding. Pallet 110 includes the deck 112 having an upper support surface 118 upon which goods can be supported. The upper surface 118 is defined by an upper planar portion 119 of the deck 112. Feet 114 project downward from the deck 112 to support the deck 112 above the floor. Openings 116 are formed in the upper surface 118 of the deck 112 above each of the feet 114. The openings 116 can receive the feet 114 of an identical deck 110 stacked thereon and partially received in the deck 112 for stability.

The deck 112 further includes a peripheral rib 120 extending downward from a periphery of the upper planar portion 119. Each foot 114 includes a wall 122 defining a periphery of the foot 114. The wall 122 of each foot 114 is recessed from the upper surface of the deck 112 and terminates approximately 1/3 of the height of the peripheral wall 120 of the deck 112 below the upper surface 119 of the deck 112. The upper surface of the wall 122 of each foot 114 protrudes inward of each corresponding opening 116 formed in the upper surface 118 of the deck 112 to form a ledge 124 about the entire periphery of the top of each foot 114.

In this embodiment, the outer portion 126 of the wall 122 of each foot 114 is spaced inward of the peripheral wall 120 of the deck 112 because the deck 112 is wider. The outer portion 126 of the wall 122 of each foot 114 may be corrugated for stiffness and strength, as shown. A plurality of ribs 128 protrude inward from the wall 122 of each foot 114 with an uppermost surface in the same plane as the uppermost surface of the ledge 124.

FIG. 13 is a bottom perspective view of the pallet 110. The pallet 110 includes a plurality of intersecting ribs 130 extending downward from the upper planar portion 119 (FIG. 1) of the deck 112. The ribs 130 extend downward to a plane containing the lowermost edge of the peripheral wall

120. Gussets 123 may connect the peripheral wall 120 of the deck 112 to the wall 122 of the feet 114.

FIG. 14 is a section view through one of the feet 114 of the pallet of FIG. 12, taken along line 14-14 of FIG. 12. As shown, the ledge 124 is recessed downward from the upper planar portion 119 of the deck 112. The outer portion 126 of the wall 122 of the foot 114 is spaced inward from the peripheral wall 120 of the deck 112. Each recess 116 is closed to the outside or the periphery of the pallet 110 by the peripheral wall 120 and an inner peripheral wall 125. In this manner, the deck 112 of this embodiment is wider than the deck 10 of the previous embodiment, with the feet 14, 114 having the same spacing.

FIG. 15 is a side view of the pallet 110 of FIG. 12. FIG. 16 is an end view of the pallet 110 of FIG. 12. FIG. 17 is a top view of the pallet 110 of FIG. 12. FIG. 18 is a bottom view of the pallet 110 of FIG. 1.

FIG. 19 is a perspective view of the pallet 110 of FIG. 12 with an identical pallet 110 stacked thereon. The feet 114 of the upper pallet 110 are received in the recesses 116 in the deck 112 of the lower pallet 110. The feet 114 of the upper pallet 110 are stacked on the ledge 124 and ribs 128. The corrugations in the outer portion 126 of the wall 122 of the feet 116 of the upper pallet 110 mate with the corrugations on the feet 114 of the lower pallet 110. The recesses 116 reduce the overall stacking height of the empty pallets 110 and increase the stability of the stack.

FIG. 20 is a side view of the stacked pallets 110. FIG. 21 is an end view of the stacked pallets 110.

FIG. 22 is a section view through the feet 114 of the stacked pallets 110. The feet 114 of the upper pallet 110 are received in the recesses 116 of the lower pallet 110, with the walls 122 of the feet 114 of the upper pallet 110 supported on the ledge 124 of the feet 114 of the lower pallet 110, i.e. the upper surfaces of the walls 122 of the feet 114 of the lower pallet 110.

FIG. 23 is a perspective view of the wider pallet 110 of FIG. 12 with the narrower pallet 10 of FIG. 1 stacked thereon. The feet 14 of the narrower pallet 10 are received in the recesses 116 in the deck 112 of the wider pallet 110. The feet 14 of the upper pallet 10 are stacked on the ledge 124 and ribs 128. The corrugations in the outer portion 26 of the wall 22 of the feet 16 of the upper, narrower pallet 10 mate with the corrugations on the feet 114 of the lower, wider pallet 110. The recesses 116 reduce the overall stacking height of the empty pallets 10, 110 and increase the stability of the stack.

FIG. 24 is a side view of the stacked pallets 10, 110. FIG. 25 is an end view of the stacked pallets 10, 110.

FIG. 26 is a section view through the feet 14, 114 of the stacked pallets 10, 110. The feet 14 of the upper pallet 10 are received in the recesses 116 of the lower pallet 110, with the walls 22 of the feet 14 of the upper pallet 10 supported on the ledge 124 of the feet 114 of the lower pallet 110, i.e. the upper surfaces of the walls 122 of the feet 114 of the lower pallet 110.

As shown in FIG. 27, the wider pallet 110 can also be stacked on the narrower pallet 10. The feet 114 of the upper, wider pallet 110 are received in the recesses 16 in the deck 12 of the lower, narrower pallet 10. The feet 114 of the upper pallet 110 are stacked on the ledge 24 and ribs 28. The corrugations in the outer portion 126 of the wall 122 of the feet 116 of the upper, wider pallet 110 mate with the corrugations on the feet 14 of the lower, narrower pallet 10. The recesses 16 reduce the overall stacking height of the empty pallets 10, 110 and increase the stability of the stack.

FIG. 28 is a side view of the stacked pallets 10, 110. FIG. 29 is an end view of the stacked pallets 10, 110.

FIG. 30 is a section view through the feet 14, 114 of the stacked pallets 10, 110. The feet 114 of the upper pallet 110 are received in the recesses 16 of the lower pallet 10, with the walls 122 of the feet 114 of the upper pallet 110 supported on the ledge 24 of the feet 14 of the lower pallet 10, i.e. the upper surfaces of the walls 22 of the feet 114 of the lower pallet 110.

A plurality of each of the two pallets 10, 110 can be used together in a system. The narrower pallet 10 can be used for deliveries to locations where the reduced width is advantageous and/or where the products to be carried permit the reduced width. The wider pallet 110 can be used for deliveries where an increased deck width is accommodated and/or where the products to be carried require the increased width. A mixture of the two pallets 10, 110 can be stacked together when empty to return all of the pallets 10, 110 to the distribution facility to be sorted and reused.

In accordance with the provisions of the patent statutes and jurisprudence, exemplary configurations described above are considered to represent a preferred embodiment of the invention. However, it should be noted that the invention can be practiced otherwise than as specifically illustrated and described without departing from its spirit or scope.

What is claimed is:

1. A pallet comprising:

a deck including an upper support surface and a peripheral wall extending downward from a periphery of the upper support surface; and a plurality of feet extending downward from the deck, each of the feet including a foot wall defining a periphery of the foot, an outer portion of each foot wall coterminous with the peripheral wall of the deck, wherein the outer portion of each foot wall includes vertical corrugations, the deck including an opening aligned with each of the plurality of feet, wherein the foot wall protrudes inwardly of the respective opening to form a ledge recessed downward from the upper support surface of the deck.

2. The pallet of claim 1 wherein the outer portion of each foot wall is in a vertical plane containing the peripheral wall of the deck.

3. The pallet of claim 1 wherein each foot includes a plurality of ribs projecting inward of the foot and having an uppermost surface in a horizontal plane containing the ledge.

4. The pallet of claim 1 wherein the outer portion of each foot wall is recessed downward from the upper support surface of the deck.

5. The pallet of claim 1 wherein the deck and feet are injection molded as a single piece of plastic.

6. A first pallet and second pallet in combination comprising:

the first pallet including a deck including an upper support surface and a peripheral wall extending downward from a periphery of the upper support surface, the first pallet further including a plurality of feet extending downward from the deck, each of the feet including a foot wall defining a periphery of the foot, an outer portion of each foot wall coterminous with the peripheral wall of the deck, the deck including an opening aligned with each of the plurality of feet, wherein the foot wall protrudes inwardly of the respective opening to form a ledge recessed downward from the upper support surface of the deck; and

the second pallet including a deck including an upper support surface and a peripheral wall extending downward from a periphery of the upper support surface; and a plurality of feet extending downward from the deck, each of the feet including a foot wall defining a periphery of the foot, an outer portion of each foot wall spaced inward of the peripheral wall of the deck, the deck including an opening aligned with each of the plurality of feet, wherein the foot wall protrudes inwardly of the respective opening to form a ledge recessed downward from the upper support surface of the deck.

7. The combination of the first pallet and the second pallet of claim 6 wherein the feet of the first pallet are configured to be received in the openings in the deck of the second pallet with the feet of the first pallet supported on the ledges of the second pallet.

8. The combination of the first pallet and the second pallet of claim 7 wherein the feet of the second pallet are configured to be received in the openings in the deck of the first pallet with the feet of the first pallet supported on the ledges of the second pallet.

9. The combination of the first pallet and the second pallet of claim 8 wherein the deck of the second pallet is wider than the deck of the first pallet.

10. The combination of the first pallet and the second pallet of claim 9 wherein the first pallet is stacked on the second pallet with the feet of the first pallet received in the openings in the deck of the second pallet with the feet of the first pallet supported on the ledges of the second pallet.

11. The pallet of claim 10 wherein the outer portion of each foot wall of the first pallet includes vertical corrugations.

12. The pallet of claim 1 wherein the outer portion of each foot wall is in a vertical plane containing the peripheral wall of the deck.

13. The pallet of claim 12 wherein each foot includes a plurality of ribs projecting inward of the foot and having an uppermost surface in a horizontal plane containing the ledge.

14. The pallet of claim 13 wherein the outer portion of each foot wall is recessed downward from the upper support surface of the deck.

15. The pallet of claim 14 wherein the deck and feet are injection molded as a single piece of plastic.

16. A pallet comprising:

a deck including an upper support surface and a peripheral wall extending downward from a periphery of the upper support surface; and a plurality of feet extending downward from the deck, each of the feet including a foot wall defining a periphery of the foot, an outer portion of each foot wall coterminous with the peripheral wall of the deck, the deck including an opening aligned with each of the plurality of feet, wherein the foot wall protrudes inwardly of the respective opening to form a ledge recessed downward from the upper support surface of the deck, wherein the ledges of the plurality of feet are coplanar with the deck.

17. The pallet of claim 16 wherein the ledges of the plurality of feet are coplanar with one another.

18. The pallet of claim 16 wherein the outer portion of each foot wall is in a vertical plane containing the peripheral wall of the deck.

19. The pallet of claim 16 wherein each foot includes a plurality of ribs projecting inward of the foot and having an uppermost surface coplanar with the ledges.

20. The pallet of claim **19** wherein the outer portion of each foot wall is recessed downward from the upper support surface of the deck.

21. The pallet of claim **20** wherein the deck and feet are injection molded as a single piece of plastic. ⁵

22. The pallet of claim **16** wherein the outer portion of each foot wall is recessed downward from the upper support surface of the deck and wherein the deck and feet are injection molded as a single piece of plastic.

23. A pallet comprising: ¹⁰
a deck including an upper support surface and a peripheral wall extending downward from a periphery of the upper support surface; and
a plurality of feet extending downward from the deck, ¹⁵
each of the feet including a foot wall defining a periphery of the foot, an outer portion of each foot wall coterminous with the peripheral wall of the deck, the deck including an opening aligned with each of the plurality of feet, wherein each foot includes a plurality of ribs projecting inward of the foot and having an ²⁰ uppermost surface coplanar with the deck.

24. The pallet of claim **23** wherein the outer portion of each foot wall is recessed downward from the upper support surface of the deck and wherein the deck and feet are injection molded as a single piece of plastic. ²⁵
